UNITED STATES PATENT OFFICE.

ALPHONSE M. NICKOL AND CHARLES T. SCHEIN, OF BATESVILLE, INDIANA.

HINGE.

1,329,059.

Specification of Letters Patent. Patented Jan. 27, 1920.

Application filed December 14, 1917. Serial No. 207,206.

To all whom it may concern:

Be it known that we, ALPHONSE M. NICKOL and CHARLES T. SCHEIN, citizens of the United States, residing at Batesville, in the county of Ripley and State of Indiana, have invented certain new and useful Improvements in Hinges, of which the following is a specification.

Our invention relates to new and useful improvements in hinges and particularly of the type whereby the pivot structure of the hinge is embodied between two hinged sections, such as a door and its frame.

An important object of our invention is to provide a device of the above mentioned character having its hinged structure semi-circular in cross section whereby the same may be embodied in a circular recess bored between the two sections adapted to be pivotally joined.

Another object of our invention is to provide a device of the above mentioned character which is strong, durable, inexpensive to manufacture, and efficient in practice.

Other objects and advantages will be heard during the course of the following description.

In the accompanying drawings wherein like numerals are employed to designate like parts throughout the same,

Figure 1 is a view showing the hinge adapted to two closed sections to be pivotally joined.

Fig. 2 is a side elevation of the same.

Fig. 3 is a view showing the hinge adapted to two sections, one of these sections being arranged at right angles to the other, and

Fig. 4 is a side elevation of the invention attached to the two sections, one of said sections being swung at an angle to the other.

In the drawings wherein is shown a preferred example of our invention, the numeral 5 designates the usual door and 6 the frame to which the door is pivotally joined. Our hinge consists of a pair of elongated semi-circular plates 7, having a pair of ears 8 formed upon the rear edges 50 of the plates adjacent the longitudinal edges thereof. These ears are provided with a perforation which are adapted to aline with each other and receive the pintle 9 which is upset upon each end as more clearly shown in Fig. 1. One semi-circular portion of the hinge is adapted to have its

longitudinal edges overlap the longitudinal edges of its co-acting semi-circular member when the hinge is in a closed position. At the point equidistant between the longitudinal edges of these plates 7, openings 10 are provided to receive screws 11, the purpose of which will be hereinafter set forth.

The ears 12 are formed integral with each semi-circular portion at the end of the hinge 65 opposite the pivot thereof, and are arranged intermediate the longitudinal edges of the plates 7. These ears 12 extend at right angles to the semi-circular plates 7 and are provided with openings 13 to receive the 70 screws 14. The numeral 15 designates the circular bore provided in the two sections on their longitudinal edges of the door 5 and the frame 6.

To install this hinge it is only necessary 75 to place the door in a closed position against the door frame 6 and to bore as many openings 15 as is necessary between the door and frame to provide the circular openings 15. The curved plates 7 are then inserted in 80 these openings so that the ears 12 lie in close engagement with the flat face of the door and frame. The screws 14 are then positioned in the door and frame so as to hold the ears 12 in their respective position. 85 The door is then swung at right angles to the frame as more clearly shown in Fig. 3 of the drawings so that the screws 11 may be passed through the openings 10 in the curved plates 7 and into the door and frame. 90

It will be seen that by providing a hinge of this character a great deal of time will be saved in mounting doors upon frames in that by using the old method a portion on the door and frame had to be chiseled out 95 so as to provide recesses to receive the respective plates of the hinge, but with the hinge we provide, it is only necessary to bore the necessary number of openings between the door and frame so that a semi-circular 100 recess is formed in both the door and the frame.

It is to be understood that the form of our invention herein shown and described is to be taken as a preferred example of the 105 same and that various changes in the shape, size, and arrangement of parts may be resorted to without departing from the spirit of the invention or the scope of the subjoined claim.

Having described the invention, we claim:
A hinge adapted to fit in a cavity between

two sections for pivotally connecting the sections comprising a pair of semi-circular (in cross section) plates pivoted together at their innermost ends, said plates adapted to lie in overlapped relation when in a closed position, and means for securing the hinge to the two sections.

In testimony whereof we affix our signatures in presence of two witnesses.

ALPHONSE M. NICKOL.
CHARLES T. SCHEIN.
